M. G. Hubbard,
Wood Planing Machine.
N° 11,648. Patented Sep. 5, 1854.

UNITED STATES PATENT OFFICE.

MOSES G. HUBBARD, OF NEW YORK, N. Y.

METHOD OF HANGING PLANE-STOCKS.

Specification of Letters Patent No. 11,648, dated September 5, 1854.

To all whom it may concern:

Be it known that I, M. G. HUBBARD, of New York, in the county of New York and State of New York, have invented a new and useful Improvement in Planing and Tonguing Boards; and I do hereby declare the following to be a full, clear, and exact description thereof, reference being had to the accompanying drawing, which illustrates 10 the same, in which—

The figure is a horizontal section of plan with a portion of the frame removed.

My improvement consists in the double set of planes having a movable bed between 15 them supported against rollers for carrying forward the stuff to be planed so that the two sides of a board can be successively planed without returning it back to its original place of entrance—or two boards planed 20 at the same time by which much time friction and power are saved for a given amount of work done. This part of my machine is constructed as follows: I form a suitable frame of cast iron or other materials to support the working parts as shown at (a, a,) in 25 the drawing. This frame has a series of vertical rollers (b,) stationed in frame running through its center in a straight line; on either side of these rollers there are grooves 30 in which an endless series of plates move marked (c.) These plates are like those in Browns machine and some others and need no specific description except that the two sides are leveled so that in their return they 35 form a second planing bed. These plates (c) have their bearings against the rollers placed between them—the plates being also vertical—outside these plates or movable planing beds a series of planes are set in permanent stocks, but instead of being at right 40 angles to the plane of motion they are inclined, the upper ends of the knives being set forward as shown by the drawing. This position of the knives tends to cut smoother 45 and with less force but at the same time forces the board downward against its lower edge and would in ordinary machines cause great friction—this I prevent by forming on the lower edge of the plates composing the 50 bed small projections or flanges on which the

board rests or instead thereof rollers may be substituted at that point to relieve the board from the friction caused by the sideway pressure. In the same frame (2) to which the knife stocks are affixed, two (more or less) feed rollers (d,) are placed and properly set—so that as the frame of knives is set out or in for a thicker or thinner board the feed rollers (a) maintain the same relative position. The plane stocks (e) to which the knives are attached are hung in the main frame (G) by lugs or ears (F) projecting below the edge of the plane so that the action of the plane upon the board shall tend to force the heel of stock down upon the board proportionably to the resistance of the cut—this is illustrated by sectional diagram—by which means I am enabled to employ light springs (i) to hold the heel of the plane stock down, and thus I prevent excessive resistance when not required.

To the front of the frame holding the plane stock, I affix a gage plate (K) which is to be so set as to guard against the introduction of boards too thick to be introduced 75 without breaking the machine.

The frame (c) with its planes and feed rollers is attached to the main frame (a) by any required number of screws (l) that can be geared together in any convenient way to be moved simultaneously.

Having thus fully described my improvement in planing lumber, what I claim therein as new and for which I desire to secure Letters Patent is—

1. The mode of suspending the plane stock, below the edge of the plane by which I increase the pressure on the heel of the stock as the resistance increases as above set forth and decrease the size of the springs 90 and the amount of friction attendant thereon.

2. I also claim the gage for preventing the insertion of a board of improper thickness as specified.

M. G. HUBBARD.
